(57) CLAIM

The ornamental design for a light stake, as shown and described.

DESCRIPTION

FIG. 1 is a perspective view of the light stake showing my new design;

FIG. 2 is a perspective view thereof from another angle;

FIG. 3 is a front and rear elevational view thereof;

FIG. 4 is a left and right side elevational view thereof;

FIG. 5 is a top plan view thereof; and,

FIG. 6 is a bottom plan view thereof.

The broken lines in the figures illustrate portions of the light stake that form no part of the claimed design.
